CRYSTAL AMPLIFIER

Frederic Koury, Somerville, Mass., assignor to
 Sylvania Electric Products Inc., Salem, Mass.,
 a corporation of Massachusetts

Application July 20, 1948, Serial No. 39,665

13 Claims. (Cl. 317—235)

1 This invention relates to semi-conductors, and particularly to semi-conducting crystals such as germanium, useful for electrical purposes such as rectification, amplifiers and the like.

A point contact to such a crystal gives a rectifying action, and the addition of one or more additional contacts close to the first will allow the device to be used as an amplifier. The setting of two contacts very close to, but spaced from, each other introduce considerable difficulty.

My invention facilitates the arrangement of said contacts on the crystal, simplifies the device together with making it more rugged and more stable in adjustment.

A feature of the invention is the use of one or more concentric contacts bearing on the crystal. A further feature is a wire contact surrounded by an insulating layer which is in turn surrounded by a metallic layer. Several sequential layers of insulation and metal may be used to produce a number of contacts.

Other objects, features and advantages of the invention will be apparent from the following specification taken with the accompanying drawing in which:

Figure 1 shows in section a crystal assembly according to the invention;

Figure 2 shows a cross-section through the contact wire and its surrounding layers; and

Figure 3 is a cross-section of a modification of the device in Figures 1 and 2.

In Figure 1, the crystal 1, which may be for example, of germanium with a suitable activating impurity such as tin, has a flat surface 2, on which the contacts 3, 4 rest.

The catwhisker or contact wire 5 may be of tungsten or other suitable metal having an insulating coating 6 of a suitable material such as cellulose ester lacquer, synthetic resin or the like, in a thin film from 0.00001" to 0.01" thick although for best results the coating should not ordinarily be much more than 0.001" thick. The metal coating 7 is applied over the insulating coating.

The insulating coating 6 may be soaked in a 45 solution of stannous chloride and hydrochloric acid for about 12 minutes. After thorough rinsing in water it is then immersed in an ammonical solution of silver metals, about 8 cc. of 37% formaldehyde solution being added to each 100 cc. of silver nitrate solution. The coating 6 is then rinsed again in water, and a layer of silver plated thereon in a standard cyanide silver plating bath in the manner well known in the art. The thickness may be, for example, from 0.000001" to 0.1" as desired. A flash plate of 50 nickel is added over the silver to facilitate soldering later to the lead-in wires 8, if desired.

The outer plated coating 7 may be spot-welded to a lead-in or contact wire 8, the central wire 5 being soldered to another lead-in wire 9.

2 The composite wire 5, 6, 7 may then be bent into an S-shape, preferably with the loops 10 and 11 opposite in direction, equal and having its longitudinal axis in a single plane. The straight 5 end portions are preferably in line with each other.

The end 13 of the wire 5, 6, 7 is immersed in an acetone solution to a depth of 0.005 inch to remove the plastic layer 6 away from the ends 10 of the wire 5. Other solvents may be used if necessary or desirable for any reason.

The ends 4 of wire 5 and layer 7 may be pointed electrolytically by immersing the wire in a solution of sodium nitrite and sodium hydroxide, connecting the wire to the positive terminal of a direct current supply, of six volts, for example, and connecting the negative terminal to a nickel cathode in the solution. A current density of between about 20 and 50 amperes per square foot may be passed between the electrodes for a few seconds to form a point on the wire end 3 and a sharp edge 4 or series of circumferential points around layer 7.

The composite wire 5, 6, 7 may be cemented or 25 otherwise passed through and affixed to an insulating piece 17 and a germanium crystal brought up against the points or edges 3, 4 until the proper pressure is achieved for the resistance desired. The "back" contact 14, which is 30 shown to be a contact of comparatively large area, may be attached to the germanium or other crystal by soldering or the like, and the metal or other support 15 used to hold the crystal in position in the cylinder 16, which may be of 35 metal.

The resultant multi-electrode crystal may be used for many purposes. For example, the catwhisker 5 may be connected to a negative voltage, and the layer 7 to a positive voltage with 40 respect to back contact 14, the signal being impressed between layer 7 and contact 15, for example in series with the positive voltage. The output current will then flow in the circuit of catwhisker 5, but if desired, with the proper biasing voltage, the catwhisker 5 may be used as the signal electrode and the layer 7 as the output electrode. In one aspect this invention is a particular form of device more broadly claimed in co-pending application, Serial No. 39,367, filed July 17, 1948, by Orrick H. Biggs and assigned to the assignee hereof and which is now abandoned.

As illustrated in Figure 3 and as mentioned above several sequential layers of insulation 6, 6' and metal 7, 7' may be used to produce a number of contacts concentrically about a wire 5, and these may be energized and connected to the appropriate signal and output circuits, in dependence upon the circuit application.

What I claim is:

1. A semi-conductor unit comprising a semi-

conductive crystal, a conductor in substantially point-contact with said crystal, a contact of comparatively large area in engagement with said crystal, a coating of insulation extending along the longitudinal surface of said conductor, and a metallic layer over said insulating coating and encircling said coating, the end of said layer being of progressively reduced thickness to provide a circumferential edge encircling said conductor, said edge being in contact with said crystal.

2. A semi-conductor unit comprising a semi-conductive crystal, a conductor in substantially point-contact with said crystal, a contact of comparatively large area in engagement with said crystal, a coating of insulation extending about said conductor along its length, and a metallic layer over said insulating coating and having a sharpened end portion in contact with said crystal, the composite structure including said conductor, said coating, and said metallic layer being contoured so as to have a portion extending perpendicularly from the surface of said crystal, and having a laterally extending curved portion to afford a resilient engagement of the conductor and the metallic layer against the crystal.

3. An electrical device comprising a body of semi-conductive material, a conductor in substantially point-contact with said body, a contact of comparatively large area in engagement with said body, a film of insulation about the lateral surface of said conductor, and a metallic sheath on said insulating layer and in endwise engagement with said semi-conductive body circumferentially about the contact of said conductor with said body, the separation of the conductor and the metallic sheath at the semi-conductive body being of the order of .001 inch.

4. An electrical device including a semi-conductive body, a contact of comparatively large area in engagement therewith, and multiple concentric conductors in endwise engagement with said body, said conductors being mutually separated by insulating coating the thickness of which is of the order of .001 inch.

5. An electrical device including a semi-conductive body, a contact of comparatively large area in engagement therewith, and multiple concentrically arranged conductors in endwise engagement with said body, said conductors being separated by insulation, the composite concentric conductor and insulation structure being contoured to provide an arcuate resilient portion, and an additional portion extending perpendicularly from the semi-conductive body.

6. The method of making a composite contact for a semi-conductor unit, including the steps of depositing a layer of metal on the exterior of a length of wire having a lateral coating of insulation, and electrochemically sharpening the metal layer at its contact end.

7. The method of making a composite contact for a semi-conductor unit, including the steps of depositing a layer of metal on the exterior of a length of wire having a lateral coating of insulation, dissolving the insulation from a limited space at the end of the wire between the wire and the film, and electrochemically sharpening the metal film at its contact end.

8. The method of making a composite contact for a semi-conductor unit including the steps of depositing a layer of metal on the exterior of a length of wire having a lateral coating of insu-

lation and dissolving the insulation from a limited space at the end of the wire between the wire and the film.

9. A transistor, including a body of semiconductive material, a contact of comparatively large area on said body, and several sequentially concentric conductors in sharp contact with said semiconductive body and separated from each other by thin layers of insulation.

10. A transistor, including a body of semiconductive material, a first conductor in substantially point-contact with said body, a contact of comparatively large area in engagement with said body, a thin layer of insulation about the lateral surface of said conductor, a second conductor engaging said body and surrounding said insulation and minutely spaced from said first conductor by said insulation, a further layer of insulation on said second conductor, and a further cylindrical contact, in sequence, surrounding said further layer of insulation.

11. A transistor, including a semiconductive crystal, a base contact on said crystal, an insulated metal wire having one end in substantially point-contact with said crystal, a first cylindrical contact concentric with and encasing said wire but minutely insulated therefrom, and a second contact concentrically about said first cylindrical contacts but minutely insulated therefrom, said cylindrical contacts being in circumferential contact with said crystal about said wire contact point and permanently positioned in close proximity with one another.

12. In a multi-element concentric co-axial translating device, the elements comprising a semiconductive crystal, a base contact on said crystal, an insulated metal wire one end of which is in point contact with said crystal, a plurality of concentric cylindrical metal contacts completely surrounding said wire each being separated and insulated from the next larger by a thin layer of insulation on the outer surface of the next smaller in diameter, and each of said contacts in concentric circumferential contact with said crystal about said contact point and permanently in close proximity with adjacent circumferential contacts.

13. A semi-conductor unit comprising a semi-conductive crystal, a conductor in substantially point-contact with said crystal, a contact of comparatively large area in engagement with said crystal, a coating of insulation extending along the longitudinal surface of said conductor, and a metallic layer over said insulating coating and encircling said coating, the end of said layer being of progressively reduced thickness to provide a circumferential edge encircling said conductor, said edge being in contact with said crystal, said insulating coating extending close to but spaced from the engagement of said point-contact conductor with said crystal.
